A. H. SCHAEFER

VALVE SEATING MACHINE

Filed July 10, 1922

FIG. 1.

FIG. 2.

FIG. 3.

FIG. 4.

INVENTOR
ALBERT H. SCHAEFER

BY *Elmer B. Johnson*
ATTORNEY

UNITED STATES PATENT OFFICE.

ALBERT H. SCHAEFER, OF COLUMBUS, INDIANA.

VALVE-SEATING MACHINE.

Application filed July 10, 1922. Serial No. 574,110.

To all whom it may concern:

Be it known that I, ALBERT H. SCHAEFER, a citizen of the United States, residing at Columbus, in the county of Bartholomew 5 and State of Indiana, have invented certain new and useful Improvements in Valve-Seating Machines, of which the following is a specification.

This invention relates to valve seating 10 machines and is designed primarily for use in connection with internal combustion engines, although the same may be used for seating valves used for different purposes, and the prime feature of the invention is the 15 provision of means for successively delivering blows to the valves for forcing them against their seats, the force of the blow delivered removing any inequalities between the surfaces of the valves and their seats 20 thereby forming a perfect fit between these parts.

A further feature of the invention is the provision of means for adjusting the parts 25 of the mechanism for adapting the device for use in connection with motors having a greater or less number of valves and seats, and for adjusting them to operate upon valves spaced different distances apart.

And a further feature of the invention is 30 the provision of means for yieldingly supporting the valves for causing said valves to rotate incident to the delivery of blows thereto, thereby forming a perfect surface circumferentially of both the valve and its 35 seat.

Other objects and advantages will be hereinafter more fully set forth and pointed out in the accompanying specification.

In the accompanying drawings, 40 Figure 1 is a top plan view of the machine as applied to use,

Figure 2 is an end elevation thereof,

Figure 3 is a detail sectional view as seen on line 3—3 Figure 1, and

45 Figure 4 is a sectional view as seen on line 4—4, Figure 2.

Referring to the drawings, 1 indicates a base, at one end of which is formed a block 2 upon which the head 3 of the motor is 50 adapted to rest when the valves are being seated. Extending upwardly from the base 1 are standards 4 in the upper ends of which is mounted a shaft 5, and to said shaft is fixed a pair of cams 6 and 7, one cam being 55 preferably positioned at right angles to the other so that when one cam is in operation

the other will be inoperative. The cams 6 and 7 are preferably flat in cross section and have their edges rounded for contact with handle portions 8 of hammers 9, one end of 60 the handle portions 8 being connected with collars 10 which are adjustably mounted upon a shaft 11, which shaft is in turn mounted in standards 12 projecting upwardly from the base 1.

The hammers 9 are so positioned that when elevated by the cams 6 and 7 they will deliver a blow to the valves 13 of the motor head when the cams are operated to release the hammers, thereby driving the valves 13 70 against their seats 14 formed in the upper face of the motor head 3. The cams 6 and 7 are each of sufficient length to operate a plurality of hammers simultaneously, and by arranging one of the cams at right angles to the other, one set of the hammers will deliver a blow, while the other set is being elevated thereby reducing the vibration incident to the delivery of the blows to a minimum.

In order to reduce to a minimum the wear 80 on the handles 8 incident to contact with the edges of the cams, plates 15 of relatively hard material are attached to the under faces of the handle portions 8 and in position to be contacted by the cams as the cams are rotated.

In order to prevent the valves remaining 85 seated after each blow is delivered thereto, and at the same time so support the valves 90 that they will be caused to rotate as successive blows are delivered thereto, springs 16 are introduced, preferably around the stems of the valves, which, while readily yielding when a blow is delivered to the valve, will 95 elevate the valve after each successive blow. The action of the spring incident to being depressed imparts slight rotating action to the valve, sufficient to cause the valve to contact with its seat at a different point with 100 each successive blow of the hammer on the valve, consequently the surfaces between the valve and its seat will be uniform throughout their diameter and no uneven surfaces will result.

As previously stated, the hammers and their supporting handles are preferably arranged in two groups, and as shown, six in each group, the cam 6 operating one group and the cam 7 the other, and in order to 110 cause all the hammers of each group to operate in unison, a bar 17 is extended trans-

versely beneath each group and is secured to the handles in any suitable manner preferably by introducing bolts 18 through the handle portions 8 and through slots 19 formed longitudinally of the bars 17, the threaded ends of the bolts having nuts 20 thereon for locking the handle portions in fixed engagement with the bars.

By connecting the handle portions to the bars in this manner they may be adjusted laterally for operation upon valves spaced different distances apart, and in the event a motor head having a less number of valves is being operated upon, two or more of the handle portions may be released from the bars and swung rearwardly to inoperative position. After the hammers have been elevated through the medium of the cams 6 or 7 the groups of hammers are caused to descend with force by attaching springs 21 to the opposite ends of the bars 17, the lower ends of said springs being connected to parts of the base 1, the springs being so arranged that when the hammers are elevated the tension of the springs will be increased. In order to maintain the hammers in proper alignment with the respective valves, a bracket 22 is extended upwardly from the base 1 and to said bracket are secured a plurality of guide arms 23 which are slotted to receive the handle portions 8, said arms being adjustably connected to the bracket 22 so that they may be moved laterally incident to the adjustment of the handle portions 8 for use in connection with motor heads having valves different distances apart. Any suitable means may be provided for rotating the shaft 5 and the cams 6 and 7 fixed thereto, but in the present instance a belt wheel 24 is shown connected to one end of said shaft for receiving power from any suitable source.

The form of device shown in the drawings is to be used on motor heads which are removable, but it will be readily understood that with a slight change in the base portion of the structure it will be readily adaptable for use with motors which do not have valves removable with the head, consequently necessitating the machine being positioned adjacent the side of the motor.

In operating the device, the motor head is removed and placed upon the block, or the machine positioned adjacent the motor, so as to position the valves below the hammers after which power is applied to the pulley 24 and the cams 6 and 7 rotated, this operation being continued until the valves are properly seated. In the event there are a less number of valves than are shown in the drawings, a certain number of the handle

portions and hammers connected therewith are released from the bars 17 and swung rearwardly into inoperative position thereby leaving only a sufficient number of the hammers in operative position to correspond with the number of valves to be operated upon.

Any suitable means may be provided for adjusting the motor head with respect to the hammers, or the hammers with respect to the valves upon which they are to operate.

Having thus fully described my said invention, what I claim as new and desire to secure by Letters Patent, is:

1. A valve seating machine adapted for delivering blows to the valves of a motor for driving said valves against their seats, comprising a plurality of hammers, pivotally mounted handle portions carrying said hammers, rotatably mounted cams for operating a plurality of said hammers simultaneously, means for causing said hammers to descend into engagement with the valves with force, and means for adjusting said hammers laterally.

2. In a machine for seating valves, a plurality of hammers, pivotally mounted supporting handles carrying said hammers, means for intermittently raising said hammers, means for causing said hammers to descend with force and drive the valves against their seats, and adjustably mounted guides for said hammers.

3. In a valve seating machine, a plurality of hammers adapted to drive valves against their seats, pivotally mounted supporting handles for said hammers, means for connecting said hammers and handles in groups, means for intermittently elevating the groups of hammers, means for causing all of the hammers of each group to descend and deliver a blow simultaneously, guides for said hammers, and means for adjusting said guides laterally for spacing said hammers with relation to each other.

4. In a valve seating machine, a plurality of hammers for driving valves against their seats, handle portions for operating said hammers, bars for connecting said handle portions in groups, means for adjustably connecting the handle portions with said bars, springs connected with said bars for causing said hammers to descend with force, cams for intermittently elevating said hammers, and adjustably mounted guides for said hammers.

In witness whereof, I have hereunto set my hand and seal at Indianapolis, Indiana, this 8th day of July, A. D. nineteen hundred and twenty-two.

ALBERT H. SCHAEFER. [L. S.]
